ROOF STRUCTURE

Charles L. McGee, Oklahoma City, Okla., assignor
to Ludowici-Celadon Company, Chicago, Ill., a
corporation of Illinois

Application July 28, 1937, Serial No. 156,052

8 Claims. (Cl. 108—10)

This invention relates to roof structures and particularly to tile or slate roof structures.

In structures of this character it is customary to provide a base supported upon rafters, to cover 5 this base with water proofing material, such as asphalt impregnated felt, to then place tile supporting strips in spaced relation upon the felt, and to then fasten the tile to these strips. The strips, however, are nailed to the base through 10 the felt covering, usually by toenailing, with the result that each nail perforates the felt and produces a source of leakage to the interior of the building of any water or moisture which may get through or around the tile. Furthermore, in 15 some roof structures the pan tile are fastened to the roof base by nails which also perforate the sealing felt, thereby affording further likelihood of leakage.

One of the primary purposes of my present invention is to provide a roof structure which will 20 be leak proof and wholly impervious to the passage of water therethrough, irrespective of any leakage through or around the tile as the result of breakage or otherwise.

25 In the accomplishment of this result, my invention contemplates an impervious and imperforate covering over the roof base composed of the usual asphalt impregnated felt which, because of the employment of my invention, is not 30 penetrated by nails in any portion of the roof area, thereby insuring that any water which may gain access to the space beneath the tiles will flow over the surface of the covering material to the eaves without finding any opportunity of 35 seeping through the material to the inside of the building.

More specifically my invention contemplates a 40 novel manner of securing and holding the tile supporting strips in position without recourse to nailing through the covering felt and in this manner leaving an imperforate covering surface which is wholly impervious to the entrance of water and moisture therethrough.

45 Other purposes and advantages of my invention will be further apparent as the same is better understood by reference to the following description when considered in connection with the accompanying drawings.

50 Referring to the drawings:

Fig. 1 is a fragmentary plan view of a partially 55 assembled roof constructed in accordance with my invention;

Fig. 2 is a view partially in section and partially in elevation taken on the line 2—2 of Fig. 1;

Fig. 3 is a fragmentary sectional view on the line 3—3 of Fig. 1;

Fig. 4 is a view similar to Fig. 1 showing a modified form of roof construction;

Fig. 5 is an end elevation looking upwardly 5 toward Fig. 4;

Fig. 6 is a fragmentary view of a partially assembled slate shingled roof; and

Fig. 7 is a sectional view on the line 7—7 of Fig. 6. 10

Referring now to the drawings more in detail and particularly to Figs. 1 to 3, inclusive, reference character 8 indicates the roof base formed of boards or sheathing supported upon suitable rafters, not shown. This base is covered by a 15 layer of impervious material 9 such as asphalt impregnated felt which is laid in elongated sheets or strips nailed near their upper edges to the base 8 by nails 11. The lower marginal edge of each succeeding sheet is lapped over the upper 20 nailed margin of the previously laid sheet and the overlapping margins are fixedly secured together and sealed against the entrance of moisture therebetween by the employment of suitable plastic cement or the like. 25

After one sheet or strip of covering material has been laid and secured in position, a plurality of strip holding clips 12 are secured by nails 13 or otherwise to the roof base in spaced relation along the upper edge of the previously laid sheet 30 9 as indicated in Fig. 1. Each clip comprises a flat base, the upper end of which is nailed to the roof base, as explained, and the other end is shaped to receive the tile supporting strips which are later positioned therein. While these clips 35 may be of various shapes and constructions, those herein illustrated are made from a flat piece of sheet metal which is cut intermediate its ends to permit the wings or flanges 14 to be upturned, as shown, for the accommodation there- 40 between of the tile supporting strips 15. These clips are spaced apart across the roof in accordance with the center spacing of the cap tiles 16 and after each row of clips has been secured in position the succeeding sheet of covering ma- 45 terial 9 is laid so that its lower edge overlaps the flat base portions of the clips and, when cemented down, provides an impervious and im- 50 perforate covering for the base which is not pene- trated by the clips so as to permit the entrance of moisture through the seal.

After the covering material has been laid with the clips positioned, as indicated, their upper ends being anchored to the base and their lower ends projecting above the seal, the strips 15 are 55

positioned in the clips, as shown, and are secured against displacement by nails 17 driven through the clip wings into the strips. To assist in maintaining the strips against endwise movement, angle brackets 18 may be secured to the base along the eaves against which the lower ends of the strips 15 abut, thereby adding strength to the structure.

The pan tiles 19 are now laid in position between the strips 15 and are secured in position by nails 21 extending into the strips 15. The cap tiles 16 are then positioned over the strips 15 and secured thereto by nails 22, thereby completing the roof structure.

15 It will be obvious that in accordance with my invention the tile supporting strips are securely anchored to the roof base without driving any nails or fastening means of any kind through the layer of impervious covering material. The 20 strip holding clips are anchored to the roof base beneath the covering material, while their strip holding ends project above the covering to support and retain the tile supporting strips. The 25 flat base portion of the clips which extends between the overlapping margins of the covering material does not interfere in any way with the laying or cementing of the material, nor does it provide any opening through the material which might afford access to the entrance of water.

30 In the form of my invention shown in Figs. 4 and 5, the pan tile 19 instead of being laid directly upon the covering material of the roof is supported upon strips 23 located intermediate the cap supporting strips 15. In this instance the 35 pan tile supporting strips 23 being about two inches high necessitate the cap tile supporting strips 15 being about six inches high. The total height of the roof therefore is about two inches higher than the height of the roof shown in Figs. 40 1 to 3 wherein the pan tile rest directly upon the sheets of covering material.

In the form of the invention shown in Figs. 4 and 5, twice the number of clips 12 are employed as are necessary in the construction shown in 45 Fig. 1 but their manner of attachment to the roof base and to the tile supporting strips is identical in each instance, the ultimate result being that the roof covering is imperforate and unbroken throughout its area, thereby obviating any possibility of leakage even though water might gain 50 access to the space beneath the tile.

In the form shown in Figs. 6 and 7, the base 8, the seal 9, the clips 12 and the strips 24 are assembled substantially in the manner previously described except that in this instance instead of tile being supported by the strips, the strips are all only approximately two inches high and are crossed by similar strips 25 nailed thereto and upon which the slate shingles 26 are supported and to which they are attached by nails 27.

The leak proof character of this type of roof is identical with that of the two types previously explained because, as in the other instances, the 65 sheet of covering material is imperforate throughout the area of the roof and no leakage therethrough is possible even though water gain access to the space above the seal.

70 It should be apparent from the foregoing that my invention provides a leak proof roof by affording an imperforate seal beneath the tile or shingles, as the case may be, which precludes any leakage of water therethrough irrespective of the water tightness of the overlying covering, 75 whether it be of tile or shingles.

While I have shown and described those preferred embodiments of my invention which at present seem most desirable, it should be understood that the structural details are capable of considerable modification and variation without departing from the scope of the invention as defined in the following claims.

I claim:

1. In a roof structure, the combination of a supporting base, a protective covering for said base comprising sheets of impervious material arranged in overlapped relation and sealed together, clips extending between the overlapped margins of said sheets, said clips being secured at one end beneath the lapping sheet to said base and having portions exposed above said covering shaped to provide upwardly opening channels and said clips being disposed in longitudinal alignment, elongated tile supporting strips extending longitudinally of said aligned clips, each strip being seated in and anchored to a plurality of said clips, and tile or the like supported by and anchored to said strips.

2. In a roof structure, the combination of a supporting base, a protective covering for said base comprising elongated sheets of impervious material arranged in overlapped relation, the overlapping portions being cemented together, clips arranged in spaced relation along the overlapped portions of said sheets, said clips extending between said overlapped portions and having an end concealed in the overlap secured to the base and another end exposed above the covering formed to provide spaced apart upwardly extending legs, elongated tile supporting strips each 35 extending between and secured to the legs of a plurality of said clips, and tile or the like supported by and anchored to said strips.

3. A roof structure comprising a supporting base, a protective covering for said base formed of overlapped impervious sheets, a plurality of clips each having a flat end disposed between the overlapped sheets and an end exposed above the covering provided with upwardly projecting spaced apart legs each clip having its flat end anchored to the base, an elongated strip extending between the legs of a plurality of said clips and anchored thereto, and tile or the like supported upon and attached to said strip.

4. A roof structure comprising a supporting base, a covering therefor consisting of sheets of impervious material having overlapping margins sealed together, means for securing tile supporting strips to said base in spaced relation over said covering without perforating the covering, said means comprising clips each having a flat portion extending between the overlapped portions of adjacent sheets and anchored to the base beneath one sheet and having a strip embracing portion disposed outside the overlap, and tile supporting strips each embraced by and anchored to a plurality of said clips.

5. A roof structure comprising a supporting base, a covering therefor consisting of overlapped sheets of impervious material having their overlapped portions sealed together, clips extending between said overlapped portions, the inner ends of said clips being anchored beneath the seal to said base and the outer ends thereof being formed to provide upwardly projecting spaced apart legs, elongated tile supporting nailing strips each embraced between the legs of a plurality of said clips and secured thereto, tile or the like disposed over said strips, and means whereby the tile are secured to said strips.

6. A roof structure comprising a supporting base, a covering therefor consisting of overlapped sheets of impervious material cemented together at their overlapping margins, clips extending between the overlapped margins and anchored to said base, said clips having portions projecting above the covering and shaped to receive and embrace the side walls of tile supporting strips, elongated strips each located in a plurality of said clips and secured thereto, and tile or the like secured to said strips.

7. A roof structure comprising a supporting base, an imperforate covering therefor consisting of overlapped sheets of covering material, tile supporting strips arranged in spaced relation above the seal, and means for anchoring said strips to said base without perforating said seal, said means consisting of metal clips flat at one end and substantially U-shaped at the other, the

flat end of each clip being positioned between the overlapping margins of said sheets and anchored to said base and the other end of each clip embracing the opposite sides of a strip and being anchored thereto.

8. A roof structure comprising a supporting base, a sheet material covering therefor composed of partially overlapped sheets, elongated wooden tile supporting strips arranged in spaced relation over said covering, means for anchoring said strips to said base without perforating said covering, said means including clips having one end shaped to lie between the lapped portions of said sheets and the other end shaped to form a chair for said strips, each strip being seated in a plurality of said clips, each clip being anchored to a strip and to said base.

CHARLES L. McGEE.
